UNITED STATES PATENT OFFICE.

MARK E. FERNALD, OF SAUGUS, MASSACHUSETTS, ASSIGNOR TO C. C. BLAKE, INCORPORATED, OF BOSTON, MASSACHUSETTS, A CORPORATION OF NEW YORK.

CASTING-PATTERN.

1,266,242.

Specification of Letters Patent. Patented May 14, 1918.

Application filed October 1, 1915. Serial No. 53,638.

To all whom it may concern:

Be it known that I, MARK E. FERNALD, a citizen of the United States, residing at Saugus, in the county of Essex and State 5 of Massachusetts, have invented a new and useful Improvement in Casting-Patterns, of which the following is a specification.

The present invention relates to casting patterns and more particularly to casting 10 patterns which determine the form of the leaders used in automatic shoe machines and other sole-shaped devices having peripheral flanges thereon such, for instance, as sole cutting dies.

15 It has been proposed to perform the various operations in the manufacture of shoes automatically. In one system of automatic shoe machines the transfer of the point of operation of the tool along the work is controlled by a leader upon which the work supporting jack is mounted. These leaders usually comprise a body portion having the same form on one face as the sole of the shoe mounted upon the jack, a flange on the edge 20 of the body portion which is usually provided with teeth for engagement with the driving pinion and a bevel formed above the teeth on the exterior face of the flange at the upper side thereof. The flange also acts

25 as a guide for swinging the jack laterally to permit the tool to traverse the reverse curves of the work. One of the principal objections to the use of these automatic machines is the cost of producing these leaders 30 which vary in size and shape with the various sizes and styles of soles intended to be incorporated into a shoe. As well known to those skilled in the art it is necessary in making a casting pattern to allow for the

35 shrinkage in the casting. Furthermore, in making a leader for a shoe machine it is also necessary to allow for the "spring" of the last upon which the sole to be incorporated into the shoe is secured. The principal reason for the high cost of these leaders is that heretofore it has been necessary to employ a skilled pattern maker in order to produce a leader casting pattern having the metal shrinkage and the "spring" of the last measurements incorporated therein.

The object of the present invention is to produce a casting pattern which may be manufactured without the aid of a pattern maker or other skilled labor.

55 To the accomplishment of this object the

features of the invention relate to certain devices, combinations and arrangements of parts hereinafter described and then set forth broadly and in detail in the appended claims which possess advantages readily apparent to those skilled in the art. 60

The various features of the present invention will be readily understood from an inspection of the accompanying drawings showing the best form of the invention at 65 present known to the inventor, in which,

Figure 1 is a plan of the blank for the casting pattern provided with a flange which is built upon the blank by winding a strip of paper in layers on the edge 70 thereof;

Fig. 2 is a sectional elevation of the blank shown in Fig. 1;

Fig. 3 is an elevation, partly in section, of a machine for imparting a draft to the 75 flange of a casting pattern;

Fig. 4 is an elevation, partly in section, of a machine for beveling the exterior face of the flange at the upper end thereof;

Fig. 5 is a plan of the finished casting 80 pattern; and

Fig. 6 is a sectional elevation of the finished casting pattern.

Describing now in general terms my novel method of making casting patterns which 85 determine the form of the leaders employed in automatic shoe machines, the first step consists in the production of the flat blank for the foundation of the pattern. The flat sole-shaped blank having the shrinkage of 90 cast iron and the "spring" of the last measurements incorporated therein may be produced by projecting the edge of a sole on the last upon a plane and then enlarging the area thus produced by the amount of the 95 shrinkage of the metal used for casting the leader. Preferably I produce the blank by means of the geometrical instrument disclosed in application for Letters Patent of the United States filed by me March 22, 1915, 100 Serial No. 16,049. In this machine a feeler travels around the peripheral edge of the sole on the last. The feeler is operatively connected to a pencil arranged to travel over a plane surface and record the movement of the feeler thereon. The connections between the pencil and feeler are such that the rising and falling movements of the feeler in traveling up and down the various slopes on the sole are not transmitted to the 105

110

pencil. The movements which are imparted to the pencil by the feeler are enlarged by the shrinkage of the metal used in casting the leader. As well known to those skilled in the art it is necessary in making a casting pattern to allow for shrinkage in the casting. Furthermore, in making a leader for a shoe machine it is necessary to allow for the "spring" of the last upon which the sole 10 to be incorporated into a shoe is secured. By this means a sole-shaped area is traced having the shrinkage of cast iron and the "spring" of the last incorporated therein. With this sole-shaped area as a guide a flat 15 blank is made having the same size and shape. This sole-shaped blank is then inserted into the machine described in application for Letters Patent of the United States filed by me October 27, 1914, Serial No. 20 868,921. This machine is provided with a rotatable support for the blank; devices for supporting, guiding and feeding a strip of material, such as paper; and a pair of rolls 25 for attaching the paper to the peripheral edge of the blank and winding the paper in layers thereon. To build the guiding flange the rolls are mounted upon a carrier which tips automatically as the point of operation of the rolls is transferred around the reverse 30 curves of the blank to maintain the rolls substantially normal to the point of operation. This carrier is mounted on a swinging support which swings automatically during the rotation of the blank to permit the rolls 35 to travel around the toe and heel portions of the blank and reach the shank portions thereof. The machine is also provided with a feed accelerator which imparts an automatic pull to the supply end of the paper 40 so that the paper may be attached to the shank portions of the blank while the paper is free from tension. After the pattern is completed by this machine the draft necessary for the removal of the pattern from the sand is imparted to the pattern by a second 45 machine which is disclosed in application for Letters Patent of the United States filed by Charles C. Blake, October 29, 1914, Serial No. 869,336, to which reference is made by permission. This machine is provided with a series of rolls which simultaneously support, guide, feed and operate automatically 50 upon the pattern to impart the draft thereto and remove any roughness on the top and 55 bottom faces of the flange. The pattern upon its removal from this machine is dried and is then inserted into the machine described in application for Letters Patent of the United States filed by Charles C. Blake, 60 September 18, 1915, Serial No. 51,450, to which reference is made by permission. This machine is provided with a beveling knife and devices for supporting, guiding and feeding the pattern to transfer the point 65 of operation of the beveling knife around

the flange and form a bevel in the exterior face of the flange at the upper edge thereof. The pattern is then provided with a coat of shellac.

Referring now to the drawings a sole-shaped blank 1, of wood or paper or fiber material, having the metal shrinkage and the "spring" of the last measurements incorporated therein is provided with a laminated flange 2 which has been built upon the blank by winding a strip of paper in layers around the peripheral edge thereof.

In order to impart the draft to the flange necessary for the removal of the casting pattern from the molder's sand and to smooth the irregularities on the top and bottom faces of the flange the pattern is passed through a machine provided with a series of rolls which support, guide, feed and operate automatically upon the pattern as it passes through the machine. As shown in Fig. 3 these rolls comprise a pair of rolls 3 and 4 which engage the top and bottom faces of the body portion of the pattern, respectively, and which are also constructed and arranged to engage the inner faces of the flange and impart the draft thereto; a pair of rolls 5 and 6 which engage the top and bottom faces of the flange, respectively, and smooth the irregularities thereon; and a fifth roll 7 which engages the outer face of the flange and imparts the draft thereto.

After the draft has been imparted to the pattern the pattern is first dried and then inserted into a machine which removes the surplus stock from the exterior face of the pattern at the upper side thereof in order that the leader made from the pattern may be provided with a bevel on the upper side of the exterior face of the guiding flange. In this machine the pattern is supported upon a platen 8 and the pattern is fed over this platen by a pair of feed rolls 9 and 10 which engage respectively the inner and outer faces of the flange. The feed rolls 9 and 10 are substantially frusto-conical in shape in accordance with the shape of the draft in the flange. With this construction the rotation of the rolls 9 and 10 feeds the flange over the platen and also swings the pattern during the feed to maintain the reversely curved portions of the flange in proximity to the operating point in the line of feed. The roll 10 is dished upon its upper face 11 to permit the operation of a rotary bell-shaped cutter 12 close to the roll. By employing a bell-shaped cutter and a feed roll having its upper face dished on a curve concentric to the cutting edge of the knife a bevel 13 (Figs. 4 and 6) will be formed on the exterior face of the flange on the upper end thereof. The cutter rotates in a contra-clockwise direction in order to form a clean cut on the flange. By rotat- 120 125 130

ing the cutter in this direction there is a tendency to lift the pattern from its support. To overcome this tendency a presser foot 14 is provided which engages the top 5 face of the flange close to the operating point. The foot 14 is carried upon a guard 15 which covers the cutter 12. After the pattern is provided with the bevel 13 a fillet of beeswax 16 is placed in the angle at the 10 juncture of the flange 2 and body portion 1 (Fig. 6) in order to prevent the molder's sand from lodging in the cracks at these points. The pattern is then finished by providing it with a coat of shellac.

15 While the illustrated embodiment of the present invention is directed to a casting pattern for use in making shoe machine leaders and for sole cutting dies it will be apparent to those skilled in the art that the 20 casting pattern herein described may be advantageously employed in making other kinds of castings.

It will be clear to those skilled in this 25 class of devices and with the general objects of the present invention in view that changes

may be made in the details of structure, the described and illustrated embodiment thereof being intended as an exploitation of its underlying essentials the features whereof are definitely stated in their true scope in 30 the claims hereto appended.

What is claimed as new, is:—

1. A pattern having a sole-shaped body portion, and a laminated flange attached thereto, substantially as described. 35
2. A pattern having a sole-shaped body portion, and a laminated flange attached thereto provided with a bevel upon its exterior face at the upper edge thereof, substantially as described. 40
3. A pattern having a sole-shaped body portion, and a flange attached thereto comprising a strip of material arranged in layers on the peripheral edge of the blank and having a draft therein and a bevel formed 45 in the exterior face of the flange at the upper edge thereof, substantially as described.

MARK E. FERNALD.
